DESIGN FOR AN ELECTRIC BED LAMP

John O. Grode, Hackensack, N. J.

Application December 20, 1938, Serial No. 81,897

Term of patent 3½ years

To all whom it may concern:

Be it known that I, John O. Grode, a citizen of the United States and resident of Hackensack, in Bergen County, State of New Jersey, have invented a new, original, and ornamental Design for an Electric Bed Lamp, of which the following is a specification, reference being had to the accompanying drawing forming a part thereof.

In the drawing, Fig. 1 is a side elevational view of an electric bed lamp showing my new design. Fig. 2 is a front elevational view thereof.

I claim:

The ornamental design for an electric bed lamp, as shown.

JOHN O. GRODE.
